AUTOMOBILE WHEEL COVER

Gerald R. Thorley, Pontiac, Mich., assignor to Chrysler Corporation, Highland Park, Mich., a corporation of Delaware

Application November 16, 1959, Serial No. 58,349

Term of patent 7 years

(Cl. D14—30)

Fig. 1 is a front elevational view of an automobile wheel cover showing my new design;

Fig. 2 is a sectional view taken on the line 2—2 of Fig. 1;

Figs. 3, 4 and 5 are sectional views taken on the lines 3—3, 4—4, and 5—5, respectively, of Fig. 2; and

Fig. 6 is a sectional view taken on the line 6—6 of Fig. 1.

The essential features of my design reside in the portions shown by means of full lines in the drawing.

I claim:

The ornamental design for an automobile wheel cover, substantially as shown and described.
